TOWEL DISPENSING APPARATUS

Rudolph G. Birr, Lombard, and Albert C. Grunwald, River Forest, Ill., assignors to Steiner Sales Company, Salt Lake City, Utah, a corporation of Utah

Application February 11, 1933, Serial No. 656,282

13 Claims. (Cl. 312—38)

This invention relates to improvements in apparatus for dispensing toweling. The invention is herein shown as applied to a type of apparatus in which towel delivery is obtained as the result of pulling of the towel by the user, and in which the soiled toweling is taken up by a roll, also as the result of such pulling of the towel by the user.

An object of the invention is to provide means operable, when the supply of toweling is substantially exhausted, to cause soiled toweling to be taken up at a greater rate than the rate of delivery of clean toweling, to the end that toweling be no longer accessible and/or visible to the user, and as an indication that replenishment of clean toweling is necessary.

Another object is to provide a change speed mechanism operable in one position, and while there is yet a substantial supply of clean toweling, to cause soiled toweling to be taken up at a rate equal to the feeding rate of the clean toweling, and operable when in another position, and when the toweling supply is substantially exhausted, to cause soiled toweling to be taken up at a rate substantially greater than the feeding rate. In this embodiment, this accelerated take-up action results in the gradual obliteration of a loop of toweling which normally hangs below the cabinet and which is visible and accessible to the user.

Another object is to provide two gear trains associated with the take-up and feed rolls, one to cause the take-up roll to be driven at equal speed with the feed roll and the other to cause the take-up roll to be driven at a substantially greater speed than the feed roll, and to provide means whereby a gear of each train can be moved into and out of mesh, one gear into mesh when the other is moved out of mesh, and to provide means for automatically shifting the gears to obtain accelerated take-up roll action when the clean toweling supply is substantially exhausted.

Another object is to provide (as a part of the toweling-controlled gear-shifting means) means to prevent introduction of a roll of fresh toweling into the cabinet unless the toweling-controlled means has been moved to such a position as to assure that the gearing will be so positioned as to operate the take-up roll at equal speed with the feed roll, after the parts have been returned to dispensing position.

Features include all details of construction, 55 along with the broader ideas of means inherent

in the disclosure, or illustrated or described therein.

Objects, features and advantages of the invention will be set forth in the description of the drawings forming a part of this application, 5 and in said drawings.

Figure 1 is a vertical section taken on line 1—1 of Figure 6, showing the mechanism positioned as when there is remaining a substantial supply of clean toweling, and with the normal amount of toweling accessible and visible;

Figure 2 is a section similar to Figure 1 but showing the clean toweling supply substantially exhausted, and the mechanism tripped, and the toweling drawn up to a substantially inaccessible 15 and invisible position;

Figure 3 is a view similar to Figure 1, but showing the mechanism positioned as substantially immediately before tripping, to shift the gears to accelerate take-up action;

Figure 4 is a fragmentary view showing the idler of the gear train in mesh to drive the take-up roll by the feed roll;

Figure 5 is a fragmentary view similar to Figure 4, but showing the idler gear shifted, and out of mesh with the gear of the feed roll;

Figure 6 is a plan section taken substantially on line 6—6 of Figure 2 illustrating, among other things, the position of the yoke after tripping action, following substantial exhaustion of the 30 clean toweling supply.

Figure 7 is a view of the speed change mechanism with parts broken away to show the relative positions of all the gears and corresponding to the position of the gears in Figures 1 and 4.

The invention is embodied in a wall type of toweling dispensing cabinet. Numeral 1 indicates the outer casing of the cabinet. This casing is provided with the usual door 2 and has in its bottom an elongated slot 3 upwardly through 40 which the toweling is drawn to be connected with the take-up roll. The front edge of this bottom is spaced from the door to permit the toweling to hang below the cabinet to be grasped by the user.

Attached to the rear wall of this casing 1 is a bracket 4 which forms part of a means for smoothing out the soiled toweling before it reaches the soiled toweling roll. Also attached to the rear wall is a bracket-like extension 5 with which a portion of the gear shift plate engages for bringing the plate to latched position when the device is moved to its normal operating position within the casing 1, after introduction 50 55

of a roll of fresh toweling, all in a manner hereinafter more fully described.

Within the casing 1 is a frame, referred to herein as the swing-housing, formed of two side plates 15-16 cross-connected in the lower portion by a plate having a vertical portion 17, curved portion 18, and horizontal portion 19, the latter portion forming a bottom. The portion 19 forms a support for a roll of clean toweling 20. A second plate 21 tops the portion 17 of the first plate and extends horizontally outwardly, and its outer end is curved upwardly to lie between the feed and take-up rolls respectively indicated at 23-24. The swing-housing thus formed is pivoted by suitable means indicated at 25, the pivot being arranged at the top of the outer casing 1. This housing supports the major portion of the mechanism of the present invention, and such mechanism can therefore, after the door 2 of the casing 1 is open, be swung outwardly for facilitating introduction of fresh toweling and/or removal of soiled toweling, as well as for moving a shiftable gear mechanism to a predetermined operating position.

For holding the swing-housing in its outward position during loading or unloading, etc., a prop arm 26 is pivoted to the plate 16 as shown in Figure 1, and this arm has a stop finger engageable with the case 1 to limit this outward movement, and also has a notch which is engageable with the forward edge of the bottom of the outer casing 1, for securing the arm in propping position. Two such arms may be employed.

After introduction of a roll of clean toweling 20, and return of the swing-housing to its operating position within casing 1, the end of the toweling is first engaged with a feed roll 23, suitably journaled in plates 15-16, then it is brought around a pinch roll 21 journaled in slots 28 of the plates 15 and 16. This pinch roll operates by gravity in a well-known manner to press the toweling against the feed roll to obtain the proper frictional contact for feeding. The toweling is then brought downwardly below the bottom of casing 1 to form a loop indicated at 30, and is then brought upwardly through slot 3 around towel-smoothing edge 31 of plate 21, then around a curved smoothing surface of bracket 4, then upwardly against smoothing bar 34, thence to the soiled towel roll 35. The shaft of this roll 35 is suitably guided in slots 36 of plates 15 and 16 and rests by gravity upon the take-up roll 24.

It is understood that means, not herein shown, but well known to this art, is provided to allow withdrawal of only a limited amount of clean toweling by the user at each operation.

A characteristic feature of this invention, in combination with a type of towel dispensing mechanism which is operated by the user by pulling the towel, or with any other suitable type of towel dispensing apparatus, is the provision of means automatically operable when the fresh toweling is almost exhausted, for more rapidly winding up the soiled toweling. This operation is herein controlled by means responsive to decrease in the amount of clean toweling. The control means includes a part which engages the roll or web of clean toweling in such manner that, when the toweling is exhausted, or almost exhausted, a latching mechanism is tripped, resulting in increasing the speed of the take-up roll over that of the feed roll, to make the remaining toweling inaccessible.

Acceleration control of the take-up roll is accomplished herein by means of gear trains and a

gear-shifting mechanism. Referring first to Figure 6, which is a plan section taken substantially on line 6-6 of Figure 2: The shafts 40-41 respectively of the feed and take-up rolls 23-24 are suitably journaled in the plates 15-16 and each shaft extends outwardly beyond the plate 16. At the inner side of plate 16 are gears 42-43 respectively secured to the feed and take-up rolls. These gears are of the same size. To shaft 40 of the feed roll at the outside of and spaced from the plate 16 is fixed a second gear 45 which is of the same diameter as gear 42. Secured to the shaft 41 of the take-up roll at the outer side of and spaced from the plate 16 is a gear 46 which is smaller than any of the previously mentioned gears.

Each pair of gears 42-43 and 45-46 forms part of a gear train of which the third member is an idler gear. These idlers 52-53 are adjustable with respect to their respective trains and both idlers are carried by a shift-plate 50 which is pivoted concentrically with the shaft of the take-up roll upon an extension 51 of the plate 16 of the swing-housing. The forward or outer portion of this plate overlies and is spaced from the shaft of the feed roll as best shown in Figure 1.

In order that the feed and take-up rolls may travel at the same speed, idler gear 52 normally occupies the position shown in Figures 1, 4 and 7. This gear is always in mesh with gear 43 of the take-up roll, but can be shifted from mesh with gear 42 of the feed roll. This idler gear 52 is arranged at the inner side of the shift-plate 50, and is mounted on a stub shaft 47 carried by said plate. This stub shaft (see Figure 3) passes through an arcuate slot 48 in plate 16 of the swing-frame, said slot being concentric with the rotative axis of the take-up roll. At the outer side of the shift-plate is idler gear 53 which constantly meshes with gear 46, but which is adapted, when the shift-plate is shifted, to move into or out of mesh with gear 45. The idler gears are so mounted that both cannot be in mesh at the same time. The alternate positions of the gear 52 are shown in Figures 4 and 5, and the alternate positions of the gear 53 are shown in Figures 1 and 2.

In order that the shift-plate 50 be so held that the idler 52 remains in mesh with gears 42-43, to operate the take-up roll at equal speed with the feed roll, a latching mechanism for the shift-plate is provided. Referring to Figure 1, the lower edge 55 of the outer end of the shift-plate 50 rests upon a shoulder 56 of a weighted latch lever 57 pivoted at 58 at the outer side of plate 16 in the same plane with the gear-shift plate. This lever is so weighted that the latch tends to move in counter-clockwise direction, or so as to have its latch end move toward the shift plate. A spring 59 attached to the stub shaft idler 52 holds the outer end of the shift plate against the shoulder 56, and acts to move the shift-plate to its position in Figure 2, after tripping.

The latch lever 57 is tripped and moves from its position in Figure 1 to that shown in Figure 2, when the supply of clean toweling is substantially exhausted, and in this embodiment, this tripping means has the following construction: At the end of the feed roll shaft 40 and against the outer face of the outer gear 45 is fixed a cam 60, see Figures 2 and 6. This cam operates in and against the sides of a slot 61 of a trip arm 62 pivoted as at 63 to an arm 64 adjustably

clamped to the projecting journaling portion 65 of a wire yoke, which is also journaled in plate 15, by portion 66. The yoke 67 rests against the roll of clean toweling as shown in Figure 1.

5 Referring to Figure 6: This yoke includes the forwardly arranged central portion 68 which is used as a hand-hold to be grasped to swing the swing-frame outwardly to loading and unloading position, after the yoke has assumed the 10 position shown in Figure 2, as a result of exhaustion of the clean toweling supply.

The latch lever 57 is provided at a point outwardly from its pivot, beyond the shoulder 56, with a lateral projection 69 which normally lies 15 below the tripping extension 70 of the trip arm 62, see Figure 1, but in opposition to which said extension 70 is brought, as shown in Figure 3, by lowering of the arm 62, as a result of movement of the yoke 67 to the position of Figure 2. 20 After 70 has reached the position of Figure 3, and during continued rotation of the feed roll thereafter, the cam moves from its position in Figure 3 to that shown in Figure 2 to cause the projection 70 to engage the projection 69 of the 25 latch 57 and move it to the unlatching position shown in Figure 2, thus releasing the gear shift plate, which is then forced by spring 59 to bring gear 53 into mesh with gears 45 and 46, to drive the take-up roll at high speed, on subsequent 30 motion of the feed roll as the result of the pull on the towel. Under these conditions, the take-up roll moves at about twice its usual rate of speed, and the loop 30 is taken up to the position shown in Figure 2. It is, of course, understood that 35 idler gear 52 is moved out of mesh before idler gear 53 is put in mesh.

In practice, the whole loop need not be taken up at the first operation of the machine after the yoke assumes the position shown in Figure 2, but may be taken up gradually, but at a greater 40 rate. In any event, it is not for long that the loop is of sufficient size to be seen hanging below the cabinet, nor does it long remain conveniently accessible, after the mechanism is set for accelerating the rotative speed of the take-up roll.

In order that the yoke 67 be caused to positively follow up, and move to the position of Figure 2, as the clean toweling supply dwindles, a spring 75 is provided, and it is coiled around the 45 journal extension 65 and has one end acting on the arm 64 and the other end attached to the plate 16, all in a manner to force the yoke 67 in clockwise direction. Of course, the yoke is moved to the position shown in Figure 1 against the 50 tension of the spring 75.

As the swing-housing is pulled out preparatory to removal of the soiled toweling roll, and introduction of a clean toweling roll 20, a pin 77 carried by the gear shift-plate engages the camming portion 78 of resilient bracket 5 and moves the plate 50 in counter-clockwise direction to bring it to the latched position shown in Figure 1, in which the shoulder 56 of the gravity latch 57 is engaged with the corresponding outer portion 55 of the shift-plate. After removal of the soiled toweling roll, the yoke 67 is then moved upwardly to the position shown in Figure 1, and the fresh toweling is introduced. During motion 60 of the yoke from its lower position of Figure 2, to its upper position of Figure 1, the strip arm 62 is raised and swung to assume the position shown in Figure 1 with the trip projection 70 disposed above the level of the lateral projection 69 of the latch 57.

After the toweling has been pulled around the rolls in the manner indicated in Figure 1 and its end has been wrapped on the soiled toweling roll, the latch arm 26 is released and the swing-housing is swung into the cabinet.

Each time that the apparatus is operated by pulling down a length of toweling, the trip lever 62 is merely oscillated by the cam, without performing a tripping function. Just as soon as the yoke 67 falls to the position shown in Figure 2, the arm 62 is lowered to the position shown in Figure 3, and thereafter the arm is moved by the cam to the tripping position shown in Figure 2, bringing the gear 53 into mesh with the gears 45 and 46 to obtain a more rapid rotation 15 of the take-up roll.

Another feature relates to means for preventing re-load, before the yoke 67 is raised from its position in Figure 2. The yoke, as herein shown, is made of wire and upon each forward extension 78a there is formed a U-shaped bend 79. Each bend is perpendicular to the portion 78 and projects upwardly, when the yoke is in the position shown in Figure 2. The distance between the top of these projections and the bottom of the feed roll is less than the diameter of a roll of clean toweling, so that as long as the yoke is positioned as shown in Figure 2, a roll of fresh toweling cannot be introduced. When the yoke is in up position, these projections 79 extend 20 through slots 80 in the rear wall of the swing-housing. If the clean toweling roll were placed upon the top of the yoke, the idler gear 53 would remain in mesh, as shown in Figure 2, and the take-up roll would, from the beginning, be operated at the accelerated, instead of the normal, speed.

We claim as our invention:

1. An apparatus for dispensing toweling including a feed roll and a soiled toweling take-up roll, a 40 variable speed change gear mechanism for operating one roll by the other in one instance to cause the take-up roll to take up soiled toweling at a rate equal to the feeding rate, and in the second instance to cause the soiled toweling take-up 45 roll to take up soiled toweling at a rate substantially greater than the feeding rate, and means automatically operable when the toweling supply is substantially exhausted for operating the speed change mechanism to take-up soiled toweling at 50 the greater rate, said mechanism including two gear trains with a gear of each train movable into and out of mesh, one into mesh when the other is moved out of mesh.

2. An apparatus for dispensing toweling including a feed roll and a soiled toweling take-up roll, a first gear train by which one roll normally drives the other to take up soiled toweling at a rate substantially equal to the feeding rate, a second gear train for driving one roll by the other 60 to take up soiled toweling at a rate substantially greater than the feeding rate, means by which one gear of each train can be moved into and out of mesh, one into mesh when the other is moved out of mesh, and means automatically 65 operable when the clean toweling supply is substantially exhausted for shifting the gears to operate the take-up roll at the greater speed rate.

3. An apparatus for dispensing toweling including a feed roll and a soiled toweling take-up roll, 70 a first gear train by which one roll is normally driven by the other to take up soiled toweling at a rate substantially equal to the feed rate, a second gear train for controlling one roll by the other to take up soiled toweling at a rate substantially 75

greater than the feeding rate, a shiftable element upon which one gear of each train is mounted to be moved into and out of mesh, one into mesh when the other is moved out of mesh, means for 5 latching the element in a position to operate the rolls through the first train, and means operable when the clean toweling supply is substantially exhausted for tripping the latch to obtain operation of the rolls by the second train.

10 4. An apparatus for dispensing toweling including a casing and a housing therein which can be swung outwardly to facilitate removal and replenishment of the toweling, said housing having mounted thereon a feed roll and a soiled toweling 15 take-up roll, a variable speed change mechanism adapted to be set for operating one roll by the other in the first instance to take up soiled toweling at a rate equal to the feeding rate, and in the second instance to take up soiled toweling at a 20 rate substantially greater than the feeding rate, means operable when the toweling supply is substantially exhausted for operating the speed change mechanism to obtain a substantially greater take-up operation, and means separate 25 from the housing by which the change speed mechanism is set for operating the rolls as in the first instance, as a result of swinging the housing inwardly.

5. An apparatus for dispensing toweling including a casing and a housing therein which can be swung outwardly to facilitate removal and replenishment of the toweling, said housing having mounted thereon a feed roll and a soiled toweling take-up roll, a gear train by which one roll normally 30 drives the other to take up soiled toweling at a rate substantially equal to the feeding rate, a second gear train by which one roll controls the other to take up soiled toweling at a rate substantially greater than the feeding rate, means by 35 which one gear of each train can be shifted into and out of mesh with its respective companion gears, one into mesh when the other is moved out of mesh, means operable when the toweling supply is substantially exhausted for operating 40 said last mentioned means to cause the take-up roll to move at the greater speed rate, and means separate from the housing by which the gears are shifted to a position to obtain normal drive 45 of the rolls, as the housing is swung inwardly.

50 6. An apparatus for dispensing toweling including a casing, and a housing therein which can be swung outwardly to facilitate removal and replenishment of the toweling, said housing having mounted thereon a feed roll, a take-up roll, a first roll-driving means by which the rolls are normally driven to take up soiled toweling at a 55 rate substantially equal to the feeding rate, a second roll-driving means by which the rolls are driven to take up soiled toweling at a rate substantially greater than the feeding rate, means by which the roll-driving means can be alternately made operative including a movable element, means for latching the movable element in a position to obtain operation of the rolls by 60 the first driving means, means automatically operable when the toweling supply is substantially exhausted for tripping the latching means to obtain operation of the rolls by the second driving means and means separate from the housing by which the movable element is latched as the 65 frame is swung outwardly.

7. An apparatus for dispensing toweling including a feed roll and a take-up roll, means for operating the takeup roll by the feed roll respectively at equal and greater speeds than the feed

roll, including first and second gears respectively movable with the feed and take-up rolls, a support swingable on an axis corresponding to that of the take-up roll, a third gear movable with the feed roll, a fourth gear movable with the take-up roll and having a lesser number of teeth than any of the above mentioned gears, fifth and sixth gears on the swingable support constantly in mesh respectively with the second and fourth gears and adapted to be alternately moved into and out of mesh respectively with the first and third gears, and means operable when the toweling is substantially exhausted for causing the support to be shifted to put the sixth gear in mesh with the third.

8. An apparatus for dispensing toweling including a feed roll and a take-up roll, means for operating the takeup roll by the feed roll respectively at equal or greater speeds than the feed roll, including first and second gears respectively movable with the feed and take-up rolls, a support swingable on an axis corresponding to that of the take-up roll, a third gear movable with the feed roll, a fourth gear movable with the take-up roll having a lesser number of teeth than any of the above mentioned gears, fifth and sixth gears on the swingable support constantly in mesh respectively with the second and fourth gears and adapted to be alternately moved into and out of mesh respectively with the first and third gears, and means for causing the support to be shifted to put the sixth gear in mesh with the third.

9. An apparatus for dispensing toweling including a feed roll and a take-up roll, a speed change mechanism including gear trains, for operating the rolls one by the other in one instance to take up soiled toweling at a normal feeding rate, and in the second instance to operate the take-up roll to take up soiled toweling at a rate substantially greater than normal, including a shiftable gear, and means operable when the toweling supply is substantially exhausted for operating the shiftable gear to condition said speed change mechanism for obtaining take up of soiled toweling at the greater rate.

10. An apparatus for dispensing toweling including a feed roll and a takeup roll, a speed change mechanism including gear trains as the sole driving connection between the rolls, and arranged only at one end of the rolls for operating the rolls in one instance to take up soiled toweling at a normal feeding rate and in the second instance to take up soiled toweling at a feeding rate substantially greater than normal, and including shift gears, and means operable when the toweling supply is substantially exhausted for operating the shift gears to condition said speed change mechanism for obtaining take up of soiled toweling at the greater rate.

11. In a toweling dispensing apparatus, a take-up roll and a feed roll, gear trains by which the feed roll operates the take-up roll as a result of a toweling dispensing operation, including gears shiftable to obtain accelerated take-up action of the take-up roll, and means for operating said shiftable gears to condition said gear trains for accelerated take up action upon a subsequent towel dispensing operation.

12. In a toweling dispensing apparatus a take-up roll and a feed roll, gear trains by which the feed roll operates the take-up roll as a result of a toweling dispensing operation, said toweling being disposed to form a loop which is visible to the user, said gear trains including gears shift-

able to obtain accelerated take up action of the take-up roll to obliterate the loop, and means controlled by a towel dispensing operation when the towel supply is substantially exhausted for shifting said gears to condition said gear trains for accelerated take-up action and so that a subsequent dispensing operation results in accelerated action to obliterate the loop.

13. In a toweling dispensing apparatus a take-up roll and a feed roll, gear trains by which the feed roll operates the take-up roll as a result of pulling of the toweling by the user, said gear

trains including gears shiftable to obtain accelerated take-up action of the take-up roll, and means controlled by a towel dispensing operation when the towel supply is substantially exhausted for shifting said gears to condition said gear trains for accelerated take up action, and so that subsequent pulling of the towel supplies the power for obtaining the said accelerated take up action.

RUDOLPH G. BIRR. 10
ALBERT C. GRUNWALD.
